T. J. Arneson
INVENTOR
BY Victor J. Evans
ATTORNEY

UNITED STATES PATENT OFFICE.

THEODORE J. ARNESON, OF BAKER, OREGON.

EYE-TESTING APPARATUS.

Application filed January 26, 1925, Serial No. 4,898. Renewed September 4, 1926.

One object of my said invention is the provision of a peculiar and advantageous chart for exercising the extrinsic ocular muscles when the chart is rotated.

5 Another object of the invention is the provision of peculiar and advantageous means for rotating the said chart.

Another object is the provision of an eye testing apparatus designed especially for use 10 in a small room divided by a panel or partition into a compartment for the testing of eyes and a compartment for lens laboratory purposes; the door between the compartments being equipped with a mirror, and the 15 apparatus being mounted on a chair for ready adjustment so as to always test at the same angle for short and tall patients.

To the attainment of the foregoing, the invention consists in the improvement as 20 hereinafter described and definitely claimed.

In the accompanying drawings forming part of this specification:—

Figure 1 is a view showing an ophthalmic chair in side elevation and in proper relation 25 to the mirror comprised in my apparatus, the said mirror in accordance with one part of my invention being carried by the door between the compartment referred to.

Figure 2 is a front elevation illustrative 30 of the chair and its equipment.

Figures 3 and 4 are enlarged detail views 35 illustrative of the motor which I prefer to employ for the rotation of my novel chart for exercising the extrinsic ocular muscles.

Figure 5 is a face view of another chart that can be used on the driven shaft of the motor in lieu of my novel chart.

Figure 6 is an edge elevation of the chart shown in Figure 4.

40 Figure 7 is a view showing the reverse side of the said chart.

Figure 8 is a view of the chart having the red dot off the center thereof and adapted to be used in lieu of my novel chart with E and red dot combined.

Similar numerals of reference designate corresponding parts in all of the views of the drawings.

Among other elements my novel apparatus 50 comprises a mirror 1. This mirror 1 in the present and preferred embodiment of the invention is carried by a door 2 which may be and preferably is the door between compartments in a small room.

55 Arranged opposite the mirror 1 and also comprised in my novel apparatus is a chair

3 which chair may be of any appropriate type for ophthalmic purposes. I prefer for the chair 3 to comprise a back 4 adapted to be convertible from a back to a child's seat 60 and vice versa. This feature of the chair, however, is not of my invention, and hence I would have it understood that the said element 4 may be altogether omitted without affecting my invention as claimed. 65

In accordance with my invention I associate with the back 5 of the chair an upright member 6 by which is carried testing equipment generally designated by 7, the theory of my invention contemplating the patient in 70 the chair looking into the mirror and seeing the testing means 7. The upright member 6 is adjustably connected at 8 to the back 5 by the means illustrated or by any other means appropriate to my invention in such 75 manner that the member 6 can be quickly and easily adjusted in a vertical direction relative to the back 5 and adjustably fixed with respect to the back 5, this provision being important inasmuch as it adapts the apparatus for testing at the same angle the 80 eyes of short and tall patients seated in the chair. A portable mirror is also used close up in front of the patient for straightening difficult cases of cross eyes. 85

An essential and highly important part of the testing apparatus referred to is a chart or disk 9 which is of my invention, the said chart or disk 9 being adapted to be rotated at a variable rate of speed and being characterized by a red dot 10 off its center and by a letter E, designated by 11. The said chart 9 characterized as stated is calculated to drive and hold fusion much more effectively than any means extant for the purpose, and 90 it is also of my invention to employ a motor to rotate the said chart or disk 9 at any speed desired. Manifestly the said chart 9 when rotated is adapted to very effectively hold the attention of a patient, and it is also 95 adapted to be used to advantage in a well lighted room as distinguished from the old practice in which patients are treated in a dark room with the assistance of only a small steady light. As illustrated the chart 100 or disk 9 is arranged in front of a letter chart 12 and a casing 13, said chart and casing being connected with and adjustable on a chair back 5 when the upright member 6 is adjusted. Also connected with the upright member 6 is an incandescent electric lamp 14 disposed in a shade 15, the current 110

for the said lamp being controlled by a switch 16, Figure 3, carried by the said casting 13.

For the purpose of rotating the chart or disk 9 about its axis I employ by preference the motor shown in Figures 3 and 4, the drive shaft of which is designated by 17. I prefer in practice to removably arrange the chart 9 on the driven shaft 17 so that the 10 said chart may be removed when desired to give place to charts such as shown in Figures 5 to 8. The motor alluded to includes a rotary casing 18 and designed to contain a spring (not shown), a shaft 19 having a gear 20 in mesh with a gear 21 on the casing 18, a shaft 22 rotatable by the spring of the casing 18, said spring being tensioned by rotation of the casing 18, a gear 23 on the shaft 19 and meshed with a gear 24 on the 20 driven shaft 17, a spur gear 25 on the shaft 17, a shaft 26 having a disk 27 and also having a pinion 28 meshed with a spur gear 25, a stop or brake 29 adjustable in the casing 13 and adapted for cooperation with the disk 25 27, a drum 30 on the shaft 19, and a cable 31 connected to and adapted to be wound on the drum 30 and also adapted to be drawn off the drum 30 with a view to winding or putting under tension the spring referred 30 to. Manifestly when the spring of the motor is put under tension, disengagement of the stop or brake 29 from the disk 27 will

be attended by rotation of the shaft 17 and the chart or disk mounted thereon.

I have entered into a detailed description 35 of the construction and relative arrangement of the parts embraced in the present and preferred embodiment of my invention in order to impart a full, clear and exact understanding of the said embodiment. I do 40 not desire, however, to be understood as confining myself to the specific construction and relative arrangement of parts inasmuch as in the future practice of the invention various changes and modifications may be made 45 such as fall within the scope of my invention as defined by my appended claim.

Having described my invention, what I claim and desire to secure by Letters-Patent, 50 is:—

In eye testing apparatus, the combination of supporting means, a motor on said supporting means, and a disk mounted for continuous rotation by the motor and having on its face an eccentric red dot and a colored 55 letter E, with a chair on which the testing apparatus is supported and relative to which the testing apparatus is adjustable, and the apparatus being arranged to be observed with the aid of a mirror by a patient seated 60 in the chair.

In testimony whereof I affix my signature.

THEODORE J. ARNESEN.
